SAWDUST BURNER

Filed Dec. 24, 1928

INVENTOR
ANDREW A. HALDEN

BY
Cook & Robinson
ATTORNEY

UNITED STATES PATENT OFFICE

ANDREW A. HALDEN, OF SEATTLE, WASHINGTON

SAWDUST BURNER

Application filed December 24, 1928. Serial No. 328,077.

This invention relates to sawdust burners and it refers particularly to burners of the gravity feed type and to an improved means associated with the burner grates for the elimination of explosions that are resultant to clogging or choking of the hopper and then a sudden dropping of a large mass of sawdust into the fire box.

Explanatory to the invention, it will be here stated that in sawdust burners of this type, as are now quite extensively used, explosions are quite frequent because of clogging of the sawdust in the hopper, with a subsequent dropping of the material after 15 that in the fire box has burned out. This dropping of the mass of sawdust into the fire box or ignition chamber naturally closes off all of the air draft and circulation, thus causing an explosion. Such explosions are 20 not only annoying but are also dangerous and many residence fires have resulted from this cause.

In view of the above, it has been the principal object of this invention to provide means 25 whereby complete clogging of the fire box by the fuel is not possible, and whereby an air passage is always maintained through the fire box for the flow of air to the combustion chamber so that explosions are prevented and 30 a more complete combustion of fuel than heretofore is insured.

More specifically, the invention resides in the provision of an air draft bridge of a novel construction that is adapted to be 35 mounted on the grate bars of the burner so as to maintain an open air passage through the fire box and into the combustion chamber; this bridge being disposed lengthwise of the fire box and transversely of the grates, and is 40 so constructed as to form a dividing ridge with outwardly and downwardly inclined, opposite side walls provided with lateral openings for the distribution of air to opposite sides of the fire box and also for the admittance of a certain amount of sawdust 45 into the air draft passage provided by the bridge.

Other objects of the invention reside in 50 the various details of construction and in the

combination of parts, as will hereinafter be described.

In accomplishing these and other objects of the invention, I have provided the improved details of construction, the preferred 55 forms of which are illustrated in the accompanying drawings, wherein—

Figure 1 is a vertical cross section taken lengthwise of a burner fire box, showing the arrangement of the air draft bridge upon 60 the grate bars.

Figure 2 is a vertical cross section taken on the line 2—2 in Figure 1, illustrating the ridge-like character of the air draft bridge.

Figure 3 is a perspective view of the air 65 draft bridge as mounted on the grate bars.

Referring more in detail to the drawings—

1 designates what may be a furnace of any of the ordinary types of construction, having an opening 2 adjacent the base thereof into 70 which the end portion of the sawdust burner fire box is extended. The burner, in its entirety, is designated by reference numeral 3 and this may be one of any of the ordinary types as are now generally in use. As here 75 shown, the burner comprises the metallic fire box portion 4, which is of rectangular, cross section, as indicated in Figure 2, and is provided at the outer end with an opening 5 over which a door 6 is hingedly suspended. The 80 door is provided with the usual damper 7 that is adjustable for regulating the flow of air into the fire box. In the top wall of the fire box, toward the forward end thereof, is an opening 8 through which the lower end of a 85 feed hopper 9 is extended for the delivery of fuel by gravity flow into the fire box and onto the grate bars. In Figure 1, the fuel, which may be sawdust or the like, is indicated at 10 and as it flows from the hopper it is directed 90 onto the grates by means of an upwardly inclined plate 11.

In the device illustrated, there are a plurality of grate bars 12 arranged in downwardly stepped relation from the outer end of the fire box to the inner end; the grates being spaced so as to leave air passages 13 between each of the adjacent bars. The grate bars are supported at their opposite ends by the opposite 95 side frames 15 which are disposed closely ad- 100

5 jacent the side walls of the fire box and the fire box is lined, as is the usual practice, with a suitable fire brick 16 to prevent overheating of the metallic outer walls and also for the purpose of confining the heat within the burner.

10 The gist of the present invention resides in the provision of the air draft bridge bar 17 which is disposed upon the grate bars, as is shown best in Figure 3, so as to extend from the lower end of the plate 11 and above the adjacent grate bar toward the inner end of the fire box; the bridge bar terminating just within the passage which leads into the furnace. This bridge bar is disposed centrally of and lengthwise of the fire box and transversely with respect to the grates. It is of metal construction, cast or otherwise formed, and is in the form of a pointed ridge whereby 15 the flow of sawdust from the hopper is divided and directed toward opposite sides of the fire box. In cross section, the bridge is of inverted, V-shape and which provides an air passage 20 lengthwise within it for the flow of air from the forward end of the box, as admitted through the air draft damper in the door, to the combustion chamber. In the sloping, opposite side walls of the bridge are 25 openings 21 for the admittance of a certain amount of sawdust into the air passage or for the delivery of air to the opposite sides of the fire box.

20 While I have illustrated the air draft bridge as being associated with a burner embodying stepped grate bars, it is not intended that it be confined in its use only to this arrangement, but that it may be designed for use in burners using stepped grates, flat grates or grates of other arrangement.

25 Assuming the parts to be so constructed and arranged, it is readily apparent that should the hopper mouth become clogged and the sawdust within the fire box burns away, a subsequent dropping of the mass of sawdust from the hopper into the fire box will not cause the latter to become clogged for the reason that the bridge bar at all times maintains an air draft passage which will positively prevent the occurrence of explosions that 30 otherwise would occur. The present bar also acts after the fashion of a hot air blast, since it provides for a flow of air into the combustion chamber, thereby insuring a more complete combustion of the fuel than heretofore 35 has been possible. The device also provides for easier and quicker starting of a fire and also for an easier maintenance of a fire after it has been started.

40 The arrangement of the bridge with the side openings provides for feeding of the fuel in certain amounts into the air passage and toward the center thereof. This fuel is easily and quickly ignited and is carried into the combustion chamber where complete combustion takes place.

70 It is readily apparent that various details of construction could be altered to adapt the device to various types of burners without departing from the spirit of the invention and, for this reason, it is not desired that my claims be limited only to the device as it is here shown.

75 Having thus described my invention, what I claim as new therein and desire to secure by Letters-Patent, is:

1. In a burner of the character described, comprising a fire box opening into a combustion chamber, a hopper for gravity feed of fuel into the fire box and a grate within the fire box, an air draft bridge disposed upon the grate lengthwise of the fire box; said bridge comprising inclined, opposite side walls forming a dividing ridge whereby fuel from the hopper is diverted to opposite sides of the fire box, and providing within the bridge an unrestricted air passage opening directly into the combustion chamber and supplied by air from beneath the grates.

80 2. In a sawdust burner of the character described, comprising a fire box and a combustion chamber, a series of grates within the fire box stepped downwardly toward the combustion chamber and providing passages for the inlet of air between them, and an air draft bridge disposed centrally of and lengthwise of the fire box and transversely of the grates and forming a horizontal dividing ridge for diverting fuel delivered thereonto to opposite sides of the fire box; said bridge forming an unrestricted air passage for the feeding of fresh air to the combustion chamber and comprising inclined, opposite side walls having openings therein for the admittance of air into the fire box.

85 90 Signed at Seattle, Washington, this 11th day of December, 1928.
